Primary Examiner — Katie Jane Stofko

(57) **CLAIM**

The ornamental design for a sushi, as shown and described.

DESCRIPTION

The patent or application file contains at least one drawing executed in color. Copies of this patent or patent application publication with color drawing(s) will be provided by the Office upon request and payment of the necessary fee.

- 1. Sushi
- 2. Sushi
- 1.1 : Perspective
- 1.2 : Front
- 1.3 : Back
- 1.4 : Left
- 1.5 : Right
- 1.6 : Top
- 1.7 : Bottom
- 2.1 : Perspective
- 2.2 : Front
- 2.3 : Back
- 2.4 : Left
- 2.5 : Right
- 2.6 : Top
- 2.7 : Bottom

The designs are sushi, which consist of rice and fish forming a unique and new sense of aesthetics by using two different types of sashimi on the sushi; (design 1) to make them symmetrical from front to back while touching each other longitudinally; (design 2) to form an oblique line while touching each other left and right; reproductions 1.1 and 2.1 are perspective views, reproductions 1.2 and 2.2 are front views, reproductions 1.3 and 2.3 are back views, reproductions 1.4 and 2.4 are left side views, reproductions 1.5 and 2.5 are right side views, reproductions 1.6 and 2.6 are top views, and reproductions 1.7 and 2.7 are bottom views of the design.
